MECHANICAL LEAD PENCIL

Filed Sept. 22, 1949

UNITED STATES PATENT OFFICE

2,587,786

MECHANICAL LEAD PENCIL

Karl Josef Svensson, Sundbyberg, Sweden

Application September 22, 1949, Serial No. 117,209
In Sweden November 8, 1948

1 Claim. (Cl. 120—18)

1

The present invention relates to a mechanical lead pencil of the type in which feeding and retracting of the lead is effected by the movement of a lead holding sleeve having a guide member or pin thereon relative to an outer sleeve surrounding the same and which outer sleeve has a longitudinal slot through which the pin passes to engage in a helicoidal groove provided on the inner wall of the casing of the pencil, feeding of the lead being effected by rotation of a pencil tip which is secured to the outer sleeve.

More particularly the invention relates to the provision of a safety device in a pencil of this character and which safety device permits the pin to become free of the groove at either end thereof so as to avoid damage to the pencil upon excess rotation of the tip in either direction.

The invention specifically relates to the provision of a lead pencil with a safety means as above indicated in which the tip is longitudinally movable relative to the adjacent end of the casing to permit the pin to rotate free of the groove at the front end of the pencil and a movable abutment means is disposed at the opposite end of the groove and normally closes the same but is movable upon excess rotation of the tip to permit the pin to rotate free of the groove at the inner end of the same.

In pencils of this type it is known to provide safety means in the form of a plate or ring at each end of the groove in the casing and which plate or ring is pressed against the end of the casing by a spring disposed about the sleeve having the longitudinal slot therein so that if the pin passing through the slot approaches either end of the groove it can displace the plate or ring.

Accordingly, the present invention has for an object to improve the construction of the means so as to render the same more economical. A specific object, therefore, is to provide in a pencil of this character a structure in which a spring pressed ring is disposed to normally close the groove at one end of the casing while the longitudinally movable pencil tip normally closes the opposite end of the groove in the casing.

A further and more specific object is to provide in a structure of this character a single spring which acts simultaneously on the pencil tip and the ring to normally close both ends of the groove in the casing.

According to the invention, a spring means is provided only at one end of and around the outer sleeve that has the longitudinal slot therein and which spring presses against a loose plate or ring bearing upon the adjacent end of the helicoidal

2

groove in the casing wall and also against a plate or ring secured at the end of the longitudinally slotted outer sleeve remote from the pencil tip, while the other end of the outer sleeve is secured to the tip of the pencil which bears upon the other end of the helicoidal groove.

The invention will now be described with reference to the accompanying drawing which shows a longitudinal section through a pencil embodying the invention.

As shown in the drawings, the pencil includes a casing 8 having a helicoidal groove 7 on the inner wall thereof. Within the casing a sleeve 3 extends and which sleeve is provided with a longitudinal slot 4, the sleeve 3 being secured to the tip 12 of the pencil, the tip having a bore therein through which the lead passes. Within the sleeve 3 is disposed a longitudinally movable inner sleeve 1 and protruding from this sleeve is a pin 5 having a guide member 6 on the outer end thereof and which pin passes through the slot 4 of the outer sleeve so that the guide member is disposed within the helicoidal groove 7 in the casing wall. The arrangement is such that upon rotation of the pencil tip the pin and slot connection between the inner and outer sleeves and the disposition of the guide member within the groove 7 effects displacement of the inner sleeve 2 and the lead with respect to the outer sleeve and the casing.

As indicated in the drawing the inner end of the tip bears against the inner or bottom end of the casing when the pencil is held vertically and the tip further includes a portion which bears against one end of the groove 7. Bearing against the open end of the groove 7 is a loose ring 9 and in longitudinally spaced relation with respect to the ring 9 is a ring 10 which is secured to the outer sleeve 3. Between the rings spring means 11, preferably a spiral or coil spring, is disposed and which spring means urges the rings 9 and 10 in opposite directions. Since the ring 9 is bearing against the end of the groove the action of the spring in bearing against the ring 10 normally urges the tip 12 into abutting relation with the outer or bottom end of the casing. By the same token the resiliency of the spring means permits outward movement of the tip 12 with respect to the casing 8.

The arrangement is such that upon rotating the tip 12 so that the guide member 6 moves inwardly of the tip in the groove 7 until it reaches the inner or upper end of the groove and abuts against the ring 9, further rotation of the tip

will effect displacement of the ring 9 against the action of the spring 11 so that the guide member and pin rotate freely outside the end of the groove 7. On reverse rotation when the guide member is moving in the groove 7 toward the tip, the guide member on reaching the lower end of the groove will displace the tip which is secured to the outer sleeve 3 against the action of the spring 11 so that the pin and guide member will rotate freely outside the lower end of the sleeve.

It is therefore clear that I have provided a mechanical lead pencil including a casing 2 having a helicoidal groove 7 on the inner wall thereof, a sleeve 3 having a longitudinal slot 8 therein disposed within said casing, a second lead holding and feeding sleeve 1 mounted within said first sleeve and having a pin 6 thereon passing through the slot in the first sleeve and cooperating with the helicoidal groove in the casing. The pencil tip 12 has a central bore therethrough surrounding both said sleeves and secured to one end of said first sleeve 3 so that upon rotation of said tip cooperation between said pin and groove effects feeding of the second sleeve longitudinally of the casing dependent upon the direction of rotation of the tip. One end of said casing bears against the inner end of said tip and said tip has a portion bearing against one end of said groove, the tip being longitudinally displaceable relative to said casing. I provide a loose ring member 9 within said casing surrounding said first-mentioned sleeve and bearing against the other end of said helicoidal groove, a second ring member 10 within said casing and carried by said first-mentioned sleeve 3 and disposed in longitudinally spaced relation relative to said first-mentioned ring member 9 and a spring 11 between the ring members normally pressing said loose ring against the adjacent end of said groove so that upon excessive rotation of said first-mentioned sleeve in either direction the resilience of the spring and the movability of the tip with respect to the casing permits the pin to escape through the ends of the groove and rotate freely outside the respective ends of the groove.

Having now described my invention, what I claim as new and desire to secure by Letters Patent is:

A mechanical lead pencil including a casing

having a helicoidal groove on the inner wall thereof, a sleeve having a longitudinal slot therein disposed within said casing, a second lead holding and feeding sleeve mounted within said first sleeve and having a pin thereon passing through the slot in the first sleeve and cooperating with the helicoidal groove in the casing, a pencil tip having a central bore therethrough surrounding both said sleeves and secured to one end of said first sleeve so that upon rotation of said tip cooperation between said pin and groove effects feeding of the second sleeve longitudinally of the casing dependent upon the direction of rotation of the tip, one end of said casing bearing against the inner end of said tip and said tip having a portion bearing against one end of said groove, said tip being longitudinally displaceable relative to said casing, a loose ring member within said casing surrounding said first-mentioned sleeve and bearing against the other end of said helicoidal groove, a second ring member within said casing and carried by said first-mentioned sleeve and disposed in longitudinally spaced relation relative to said first-mentioned ring member, a spring between the ring members normally pressing said loose ring against the adjacent end of said groove so that upon excessive rotation of said first-mentioned sleeve in either direction the resilience of the spring and the movability of the tip with respect to the casing permits the pin to escape through the ends of the groove and rotate freely outside the respective ends of the groove.
